CONDENSER

Joseph John Thompson, Battle Creek, Mich., assignee to Kellogg Company, Battle Creek, Mich., a corporation of Delaware

Application May 2, 1938, Serial No. 205,484

1 Claim. (Cl. 257—28)

This invention relates to condensers.

The object of the invention is to provide a condenser particularly adapted for condensing the vapors of a solvent used for extracting caffeine from coffee and for other similar purposes.

With this and other objects in view which will appear as the description proceeds, the invention resides in the combination and arrangement of parts and in the details of construction, as hereinafter described and claimed, it being understood that changes in the details of the invention and in the combination of parts may be made within the scope of the claim without departing from the spirit of the invention.

15 In the accompanying drawings forming part of this specification,

Figure 1 is a perspective view of the improved condenser, part of the tank of which is broken away to show the elements within.

20 Figure 2 is a view of one of the six condensing chambers shown in Figure 1.

Figure 3 is a detailed view in vertical section on the line 3—3 of Figure 2, showing a portion of the condensation chambers.

25 Figure 4 is a detailed plan view of the overflow from the cooling tank.

Generally described, the condenser of this invention includes a cooling tank 1 into the lower portion of one end of which, cold water is introduced through a pipe 2.

The water is jetted vertically upward from the water inlet 2 through a series of jets 3. The capacity of the pipe 2 is sufficient to feed all of the jets 3.

35 Arranged in the cooling tank 1 are six condensation chambers 4—4 which extend lengthwise of the tank as indicated in Figure 1 and are spaced away from each other.

The arrangement of jets 3 relatively to the water inlet 2 is such that two of said jets are on opposite sides of each of the condensation chambers 4, as clearly shown in Figure 1, and said jets as indicated in Figure 1 are set slightly inward from the ends of the condensation chambers so that the cold water is jetted upward on both sides of each of the condensation chambers.

40 The cooling water in the tank continuously flows through the pipe 2, jets 3 and out of the tank at the opposite end through the overflow pipe 5 which maintains constant level of cooling water in the tank.

45 By locating the cold water inlet 2 at one end of the tank and the overflow 5 at the other end of the tank and by directing the jets 3 upwardly, the cold water first passes upwardly in the tank

1 and then flows towards the bottom and the overflow pipe 5 constantly drains off the warmer strata of water at the top.

The tank 1 preferably is made of wood supported on beams 8—8—8, and when the apparatus is not in use the water may be drained from the tank 1 through the drain pipe 7. The condensation chambers 4—4 are suitably supported upon sleepers or cross-bars 8—8 as shown in Figure 1.

10 The solvent which has been employed for leaching or extracting the caffeine from the coffee or other fluid to be acted upon, is vaporized and enters the apparatus through an enlarged vapor header 9, which extends transversely across the top of the tank 1 and is connected with all of the condensation chambers 4—4 by means of the down pipes 10—10, each of which extends through a flared inlet portion 11 into one of the condensation chambers 4.

15 The condensate passes out from the bottom of each of the condensation chambers 4 through a flared outlet 12, into an outlet 13 which extends into a main outlet 14, which extends transversely of the tank 1. Each of the outlet pipes 13 and 20 the inlet pipes 10 are in two sections suitably joined together by flange joints 15, which are staggered as indicated in Figure 1, so as not to interfere with each other and yet permit ready access for assembling or disassembling the tanks. 25

20 As shown in Figures 1 and 3, each of the condensation chambers 4 has extended transversely across it a series of stainless steel rivets or tubes 16, which serve to reinforce and strengthen the condensation chambers.

25 Each of the condensation chambers, as shown in Figure 1, is provided with alternating baffle partitions which are marked from the top downward as 17, 18, 19, 20, 21, 22.

It will be observed that the partitions 17, 18 and 21 are placed immediately above the rivets 16 so as to be reinforced thereby. It will be further observed that each of the partitions numbered 17, 18 and 21 extend from the center of the tank in opposite directions, and downwardly 45 sloping to a point spaced away from the ends of the tank.

It will also be observed that the partitions 18, 20 and 22 are connected with the ends of the tank and extend inwardly and downwardly to a point 50 spaced away from the center of the tank.

It will further be observed that when the vapor enters each of the condensation chambers 4 at the point 11, it passes through a restricted space defined by partition 17 and the top of the tank 4, 55

and that the gas then expands out into a wider space produced by the down incline of the partition 17 at each end.

It will also be observed that any liquid which condenses on the partition 17 tends to drip from the opposite ends thereof in the form of a cascade through which the gas passes at the restricted point formed by the partitions 17 and 18, and the gas then expands out into a large chamber and passes down at the center through the opening in the partition 18, and then repeats the same course in regard to partitions 18, 20, 21 and 22.

It will be further noted, from Figure 1 that the bottom 4—a of each condensation tank is sloped on the incline toward the outlet pipes 18 so as to

permit the condensate to flow into the outlet 14.

What is claimed as new is:

In a condenser, a tank provided with an overflow outlet for cooling water and containing a plurality of closely and parallelly spaced hollow, flat, relatively thin, vertically disposed vapor condensing units arranged in parallel and located below said overflow outlet, vapor inlet means for each of said condensing units, condensate outlet means for each of said condensing units, cooling water inlet means in said tank disposed adjacent the bottom of said tank and having inlet jets on each side of each of said condensing units, which jets are adapted to jet the incoming water onto the sides of said condensing units.

JOSEPH JOHN THOMPSON.
